UNITED STATES PATENT OFFICE.

JOHN GLOVER, OF CHICAGO, ILLINOIS.

MOP AND DUSTER CONSTRUCTION.

Application filed August 15, 1924. Serial No. 732,149.

The present improvements relate to devices of the mop and duster type for cleaning floors, walls, windows and other surfaces. Its principal objects are to provide 5 a mop or duster according to which the cleaning element, usually called a swab, may be readily applied to the frame adapted to hold and carry it, and from time to time be readily removed therefrom, as for cleaning 10 the swab or the frame, making repairs or replacing an old swab with a new one; and to provide such advantages in a device of simple construction and of few parts, and which may be of various forms, shapes and 15 sizes according to particular uses or other considerations.

It is not broadly new to provide a mop or duster having a removable swab, but so far as I am aware no such device has been suggested, prior to my present invention, according to which the swab may be applied or removed without considerable labor, patient effort, and loss of time.

In the accompanying drawings, which 25 form a part of this specification, Figure 1 is a perspective of a preferred form of the improvements as embodied in a mop or duster of the elongated body type; Fig. 2 is a top plan of the device of Fig. 1 with the 30 handle bracket broken away; Fig. 3 is a sectional view on the line 3—3 of Fig. 2; and Fig. 4 is a fragmentary section as on the line 4—4 of Fig. 2.

Referring to Figs. 1 to 4, the device illustrated includes a body member or frame 10 of elongated form having flanges 11 integrally formed at each side thereof. These flanges are shown as upstanding, this arrangement being preferred since it leaves 40 the bottom of the frame free of projecting parts likely under some conditions to contact and mar furniture or other objects being cleaned, and it also avoids some injury to the swab elements through rubbing contact if 45 the flanges depended from the top surface of the frame.

This sheet-metal frame 10 is shown as being relatively wide at 12—12 and at 13—13, and as tapering thence toward the ends respectively, where the frame is relatively narrow. At each end there is an integral projection 14 extending in the longitudinal directions of the frame. At 15, 16, 17 and 18 respectively I have shown a sharp prong or tooth formed from the metal and extending outward from the side wall or flange.

The cleaning element 17, usually called a swab, is to be understood as consisting of strands or lengths of cord, yarn or the like secured together and covered along one edge 60 portion with a fabric binding 17^a. The construction of such and other cleaning elements suitable in the present device is well known and the one illustrated may be considered of any approved manufacture as to details. 65 It differs from hitherto-suggested swabs, so far as I am aware, in being continuous or in the form of an endless band or ring, the ends of a strip of swab having been stitched or otherwise secured together to produce it. 70 It is not essential, however, that the swab be in the form of an endless ring. Whether endless or divided, when normally applied to a frame such as is shown in Figs. 1, 2 or 5, it will be ring-like and will substantially 75 surround the frame and lie along marginal portions thereof, as in contact with the marginal flanges.

An eyelet 20 is preferably secured in the binding 17^a of the swab at equally-spaced 80 apart portions thereof, and when the swab is applied to the frame the projections 14 extend into these eyelets respectively, provide anchoring means for the swab, and hold the swab readily releasably upon the frame. 85

The construction provides swab material at the ends of the device, and the metal parts are effectively covered by the relatively soft material, so that the marring of furniture and other objects contacted by these end 90 parts of the device is avoided, and at the same time the presence of swab material at the ends provides means for cleaning in corners and other relatively small spaces. The studs or projections 14 preferably terminate short of the thickness of the swab 95 to avoid marring effects by their outer ends respectively.

Preferably substantially midway between the ends of the frame there is a constricted 100 or throat-like portion formed by inclining the side walls inward from the relatively wide places at 15—16 on one side and 17—18 on the other. This construction provides recesses, hollows or indentations in the frame 105 at 22 on one side and 23 on the other. When the swab is normally applied to the frame, portions of the swab extend across these recesses respectively. The swab is of slightly less lineal measurement than is the periphery or margin of the frame where the swab 110 is adapted to rest upon it. Eyelets 24 and

25 are secured in the swab binding opposite the recesses respectively.

The flanges 11 on opposite sides are apertured at the recesses to receive the transversely-directed bolt 26, and this bolt passes also through the eyelets 24 and 25. By means of the wing-nut 27 the opposite portions of the swab at the recesses 22 and 23 are drawn toward each other, and, since the swab bridges these recesses when first applied, the recesses afford space into which portions of the swab can be drawn. The threading of the thumb-nut upon the bolt draws the swab taut and in tight contact with the marginal portions or flanges of the frame.

When the swab is thus drawn taut the sharp projections 15, 16, 17 and 18 enter the fabric and serve as locking means adapted 20 to hold the swab from movement in up and down directions relative to the frame. There is very little longitudinal movement of the swab at these projections. The end projections 14 anchor the swab against the 25 pulling strains exerted by the bolt and nut, which strains, in the construction shown, come substantially equally on both sides. In some constructions, however, such strains might come principally or entirely on one 30 side, and in view of this disclosure those skilled in the art will readily perceive how a considerable variety of arrangements of parts may be had without departing from the spirit of this invention. The projections 14 also maintain the swab against up- 35 and-down relative movement at the ends of the device. While such projections as 15 to 18 might be employed at the ends, and while the marginal portions of the frame 40 may have various shapes having a view to holding the swab thereon, the construction illustrated is both effective and relatively cheap.

The handle bracket 30 is of well-known 45 form. In Fig. 2 it is shown as being apertured to accommodate the bolt 26. A similar bracket is only partly shown in Fig. 5.

According to the constructions illustrated the swab may be readily applied to and 50 removed from the frame. An important advantage of this provision is in maintaining the swab clean and sanitary, for, removed from the frame it may be easily hand-rubbed or put through a washing machine and wringer. Substitution of a new swab is also rendered easy, and thus a considerable saving may be effected during the

life of the frame part. The device is simple and of few elements, strong and durable, and the application and removal of the swab 60 can readily be accomplished by unskilled help.

I contemplate as being included in the present invention such changes, departures and modifications from what is herein specifically illustrated and described as fall 65 within the scope of the appended claims.

I claim:

1. In a mop or duster of the character described, the combination of a supporting 70 frame, an endless swab extending along marginal portions of the frame and substantially surrounding the frame, means for holding the swab in readily releasable relation to the frame at spaced apart portions of 75 the swab and frame respectively, the frame having oppositely-disposed recesses in a marginal portion thereof intermediate said holding means, and unitary means at said recesses for holding the swab readily releasably and for drawing portions of it into 80 the space of said recesses respectively to exert a binding action of the swab upon the frame for holding the swab tightly thereon. 85

2. In a mop or duster of the character described, the combination of an elongated frame having a pair of oppositely disposed recesses in the sides thereof substantially midway of the ends of the frame, the frame having means at each end for holding a swab 90 thereto so as to lie along marginal portions of the frame and extend across said recesses, and clamping means on the frame at said recesses for drawing portions of the swab toward each other and into the space of the 95 recesses respectively to draw the swab taut upon the frame.

3. In a mop or duster of the character described, the combination of an elongated frame of sheet metal having a marginal 100 flange at each side thereof and having a pair of oppositely disposed recesses in the sides substantially midway of the ends of the frame, the frame having a projection at 105 each end adapted to engage a swab readily releasably, a swab in endless ring form held by said projections and extending along said flanges and across said recesses, and a bolt extending transverse of the frame at said recesses and passing through the swab 110 for drawing portions of the swab toward each other to draw the swab taut upon said flanges.

JOHN GLOVER.
